UNITED STATES PATENT OFFICE.

FRANK R. JACK, OF GARNETT, KANSAS.

DRILLING APPARATUS.

Application filed August 21, 1922. Serial No. 583,242.

To all whom it may concern:

Be it known that I, FRANK R. JACK, a citizen of the United States, residing at Garnett, in the county of Anderson and 5 State of Kansas, have invented certain new and useful Improvements in a Drilling Apparatus, of which the following is a specification.

This invention has relation to certain new 10 and useful improvements in drilling apparatus and relates more particularly to well drills.

An object of the invention resides in the provision of a resilient mounting for the 15 temper screw of a well drilling apparatus, so as to automatically raise the temper screw when released after being lowered or screwed out.

A further object of the invention resides 20 in the provision of a resilient mounting of the character stated which will provide for automatic raising of the temper screw with the saving of labor and strain upon the apparatus and without materially increasing 25 the cost of the drilling apparatus.

The invention has for a still further object the provision of a resilient mounting of the character stated for a temper 30 screw of a drilling apparatus, which will be composed of the minimum number of parts of simple construction and arrangement and which will be highly efficient in use when incorporated in the types of well 35 drilling apparatus now in general use.

Still another object of the invention resides in the provision of a temper screw mounting of the character stated which will be placed under strain as the temper screw 40 is screwed out and which will act automatically to lift the temper screw when released, together with the cable clamps, after the temper screw has been wrung and the cable clamps released, thereby making 45 it possible to dispense with the services of at least one workman heretofore required and also reducing the load on the other workman or operator holding the clamps and relieving the temper screw of 50 a considerable amount of the strain to which it has been heretofore subjected and permitting the temper screw to be raised in one-third of the time required by the present method employed.

55 With the foregoing and other objects which will appear as the description pro-

ceeds, the invention consists in the novel construction, combination and arrangement of co-operating elements as hereinafter more specifically set forth, claimed and 60 shown in the accompanying drawings forming a part of the present application and in which:

Fig. 1 is a plan view of the mounting forming the subject matter of this invention. 65

Fig. 2 is a side elevation of the parts shown in Fig. 1.

Fig. 3 is a front elevation of the parts shown in Figs. 1 and 2. 70

Referring more in detail to the drawings in which similar reference characters designate corresponding parts throughout the several views, 1 indicates the Samson post or walking beam of a drilling apparatus, 2 the temper screw and 3 the casing for the temper screw. The clamps 4 are also shown in the drawings so that parties familiar with such apparatus may understand clearly the application of the present invention. 75 The temper screw 2 and the casing 3 therefore are of conventional form and these parts are mounted on the slotted end of the beam 1 by the T-shaped supporting bracket 5, the center member of which depends 80 through the slot 6 in the end of the beam 1, as shown clearly in Figs. 1 and 3. It will be seen by referring to Fig. 3 that the depending center member of the T-shaped supporting bracket 5 extends into the upper 85 end of the casing 3. This view also discloses, together with Fig. 2, the oppositely directed outstanding arms 7 carried by the upper portion of the casing 3. Opposite ends of the cable 8 are connected with the 90 arms 7, after which the cable is extended upwardly and over the pulleys 9 carried in the depending end portions of the cross member of the T-shaped supporting bracket 5. The cable end portions then extend in a substantially horizontal plane and pass around the rollers or guide pulleys 10 carried in the roller supporting members 11, which latter are pivoted upon the ends of the cross bar 12. These cable ends 105 then connect with the central portion of the cable which extends forwardly and passes around the stationary guide roller 13 or pulley mounted on the upper face of the beam 1 near the slotted end thereof. 110 This may be readily understood by referring to Figs. 1 and 2.

As means for supporting the movable cross bar 12 properly above the beam 1, a spring 14 is provided, one end of the spring 14 being pivotally connected with the central portion of the cross bar 12 while the opposite end of the spring 14 is connected with one end of a short chain 15. The remaining end of the chain 15 is mounted on the supporting hook 16, positioned near the central part of the beam 1 and on the upper face thereof. A stationary enclosing and protecting casing 17 is provided for the spring 14 and normally the spring is practically enclosed in the casing 17. This casing 17 has both ends open and is secured upon the upper face of the beam 1 by suitable securing members passed through the laterally extended ears 18 on opposite sides of the spring casing 17 and near the ends thereof, as shown in the drawings.

It is believed the complete mounting should now be apparent both in construction and operation, from the foregoing paragraphs taken in connection with the accompanying drawings. It may be briefly stated, however, that when the temper screw is forced down or screwed out in the usual manner, after fastening of the clamps 4, the cable 8 will be operated upon to draw the cross bar 12 toward the slotted end of the beam 1 and thereby expand the spring 14. Therefore, when the clamps 4 are released, the spring 14 will immediately act to resiliently return the temper screw to its raised or normal position and retain the temper screw in this position until again operated. This resilient mounting of the temper screw will relieve the same of considerable strain and reduce the labor and number of operators required for this oper-

ation to the minimum. It is believed that further description of the operation is unnecessary.

While the preferred embodiment of the invention has been shown and described, it should be understood that minor changes in the details of construction and arrangement of parts may be resorted to within the scope of what is claimed without departing from the spirit of the invention.

What is claimed is:

1. A resilient mounting for a temper screw of a drilling apparatus comprising the combination with the temper screw and the supporting beam therefor, of a cable connected with said temper screw, a spring mounted on said beam, a cross bar carried by said spring, guide pulleys mounted on said cross bar, a stationary guide pulley mounted on said beam, said cable being extended around said guide pulleys, and a protecting casing for said spring.

2. A resilient mounting for the temper screw of a drilling apparatus comprising the combination with the temper screw, clamps and supporting beam, of means for mounting said temper screw on one end of said beam, a supporting spring connected by one end with said beam, an open ended casing for said spring, means for securing said casing upon said beam, a cross bar carried by said spring, a flexible supporting member connected with said cross bar and with said temper screw, whereby said temper screw is resiliently retained in its normal raised position, and guide members for said flexible supporting member.

In testimony whereof I, affix my signature.

FRANK R. JACK.
